(57) **CLAIM**

The ornamental design for a massager attachment, as shown and described.

DESCRIPTION

FIG. 1 is a perspective view of a massager attachment, showing our new design.

FIG. 2 is a rear elevational view of the massager attachment of FIG. 1.

FIG. 3 is a front elevational view of the massager attachment of FIG. 1.

FIG. 4 is a right side elevational view of the massager attachment of FIG. 1.

FIG. 5 is a left side elevational view of the massager attachment of FIG. 1.

FIG. 6 is a top plan view of the massager attachment of FIG. 1; and,

FIG. 7 is a bottom plan view of the massager attachment of FIG. 1.

The broken lines shown in the figures are for the purpose of illustrating portions of the massager attachment, which form no part of the claimed design.
